Primary Examiner — Lakiya G Rogers*Assistant Examiner* — Carissa C Fitts(74) *Attorney, Agent, or Firm* — Wang Law Firm, Inc.(57) **CLAIM**

The ornamental design for a work light, as shown and described.

DESCRIPTION

FIG. 1 is a front view of the work light showing my new design;

FIG. 2 is a left view thereof;

FIG. 3 is a right view thereof;

FIG. 4 is a rear view thereof;

FIG. 5 is a top view thereof;

FIG. 6 is a bottom view thereof;

FIG. 7 is a front perspective view thereof;

FIG. 8 is a front perspective view thereof; and,

FIG. 9 is a front perspective view thereof with two side panels spread.
The broken lines show portions of the article which form no part of the claimed design.**1 Claim, 9 Drawing Sheets**(56)
